UNITED STATES PATENT OFFICE.

NEWEL D. GOFF, OF PROVIDENCE, RHODE ISLAND.

AIR HEATER FOR FURNACES.

Application filed March 9, 1923. Serial No. 623,983.

To all whom it may concern:

Be it known that I, NEWEL D. GOFF, a citizen of the United States, residing at Providence, in the county of Providence and State of Rhode Island, have invented certain new and useful Improvements in Air Heaters for Furnaces, of which the following is a specification.

This invention relates to improvements 10 in fuel saving attachments for stoves, boilers and furnaces of the type where an air inlet is arranged to deliver heated air in the top part of the firepot.

It belongs to the class of such devices 15 peculiarly adapted for furnaces of all kinds in which it is desired to burn a poor grade of hard coal, soft coal, buckwheat, or other similar fuel which, under ordinary conditions, burns with difficulty, if at all.

20 By the use of my device, the amount of clinkers and ashes is greatly reduced and the efficiency of the fire much increased.

My device, preferably, is attached to the fire door and is so arranged that the amount 25 of air entering therethrough can be regulated in accordance with the fuel and other conditions and will rapidly be heated by contact with the outside of my device which is of peculiar form. The air inlet is so positioned that the heated air will be delivered just above the level of the coal at the front, as I claim by this arrangement much better 30 results are produced than when heated air is delivered at the top of the fire box or fire dome.

In the drawings, Figure 1 is a sectional side elevation on line 1—1 of Fig. 2 of a common form of furnace with my device in position.

40 Fig. 2 is a front elevation showing the front door of a furnace equipped with my device showing the damper open.

Fig. 3 is a vertical section on line 3—3 of Fig. 1.

45 Fig. 4 is a diagrammatic sectional elevation showing the relative size of parts in an ordinary round boiler.

In the drawings, T represents the fire box of a furnace of any ordinary type having 50 walls such as 11 and what I might call the fire pot, the walls of which extend upward as far as 12, forming a water jacket 5.

55 10 represents the opening for fire door H which may be hinged in the usual manner at 9. Through this door I cut an opening

15 which, as shown, is preferably of circular form.

B represents a cover of cap shape having a protruding center and a squared flange 8 through which are suitable bolt holes 7, 7, 60 7, 7 by which it is fastened in position outside door H so as to cover opening 15.

A represents an adjustable damper pivoted at 6 to cover B and having triangular shaped holes 22 which register with similar 65 holes 20 in cover B. M is a handle for the damper.

Preferably, a scale 21 is marked on cover B and with this engages pointer 4 on the damper A whereby the extent of adjustment 70 may be read and, if necessary, regulated.

Inside the cap part of cover B, I locate an air distributing plate C having air holes 24 near its periphery whereby the air entering through the openings 22 and 20 is directed towards the outside of the inside of the goose neck or conduit to be described.

The fins 66 and 67 position the plate C and hold it in place.

F represents a goose neck which has a circular opening around which is a square flange 80 which has four holes 31, 31, 31, 31 through which pass the bolts 16 and 16 which also pass through the holes 68, 68, 68, 68 in door H and 7, 7, 7, 7 in cover B. 85 By means of these bolts and holes the parts can easily be assembled or taken apart.

At the point 32 this goose neck is constricted and swells out at 37, at which point I arrange a baffle plate D supported by 90 means of four ears 34 whereby the course of the current of air is kept around the outside where it should be most rapidly heated.

At 35 the goose neck extends in to its farthest point in the fire box and thence extends back and down at 36 and has a nozzle 37 which is so positioned that it will be level with the bottom of the door.

My whole device swings out when the door is opened in order to feed coal, and it is desirable that the coal should be piled up from the point 2 near the door to the point 3 near the center whereby the hot air entering at 37 spreads directly around the pile of coal thus greatly aiding combustion.

105 I claim:

1. The combination with the fire door of a furnace having a circular opening; of a cover fixed outside said door so as to cover such opening; an adjustable damper in said 110

cover; an air distributing plate having air holes near its periphery fixed inside said cover; a goose neck fixed to the inside of said door over said opening and extending 5 thence inward, thence back and down to a nozzle on a level with and proximate the bottom of said door; and a substantially circular baffle plate fixed medially in said goose neck to cause the air to circulate closely inside the walls of the goose neck.

2. The combination with the fire door of a furnace having an opening; of a cover fixed outside said door so as to cover such opening; an adjustable damper in said 15 cover; a goose neck fixed to the inside of said door over said opening and extending thence inward, thence back and down to a nozzle on a level with and proximate the bottom of said door; and a substantially circular baffle plate fixed medially in said goose 20 neck to cause the air to circulate closely inside the walls of the goose neck.

3. The combination with the fire door of a furnace having a circular opening; of a 25 cover fixed outside said door so as to cover

such opening; an adjustable damper in said cover; and a goose neck fixed to the inside of said door over said opening and extending thence inward, thence back and down to a nozzle on a level with and proximate the 30 bottom of said door.

4. The combination with the fire door of a furnace having an opening; of a goose neck fixed to the inside of said door over said opening and extending thence inward, thence 35 back and down to a nozzle on a level with and proximate the bottom of said door.

5. The combination in a furnace having a fire door opening; of a fire door so pivoted as to open and close such opening, and itself 40 having an opening; and a goose neck fixed to the inside of said door over said door opening and extending thence inward, thence back and down to a nozzle on a level with and proximate the bottom of said door and so 45 formed and positioned that it can swing in and out of said fire door opening with the fire door.

NEWEL D. GOFF.
